UNITED STATES PATENT OFFICE.

ADAM C. WILLIAMS, OF RAVENNA, OHIO.

DESIGN FOR A TOY BANK.

No. 38,165.

Specification for Design.

Patented Aug. 14, 1906.

Application filed June 11, 1906. Serial No. 321,299. Term of patent 14 years.

To all whom it may concern:

Be it known that I, ADAM C. WILLIAMS, a citizen of the United States of America, residing at Ravenna, in the county of Portage and State of Ohio, have invented a new, original, and ornamental Design for a Toy Bank, of which the following is a specification, reference being had to the accompanying drawings, forming part thereof.

In the drawings, Figure 1 is a front elevation of a toy bank embodying my ornamental design. Fig. 2 is a rear elevation of same. Fig. 3 is a side elevation of same.

I claim—

The ornamental design for a toy bank as shown.

ADAM C. WILLIAMS.
